UNITED STATES PATENT OFFICE.

REINHOLDT BORCHERDT, OF SOUTH KAUKAUNA, WISCONSIN.

VALVE-GEAR.

1,137,112.

Specification of Letters Patent. Patented Apr. 27, 1915.

Application filed October 1, 1914. Serial No. 864,394.

To all whom it may concern:

Be it known that I, REINHOLDT BORCHERDT, a citizen of the United States, residing at South Kaukauna, Outagamie county, Wisconsin, have invented certain new and useful Improvements in Valve-Gears, of which the following is a specification.

This invention relates to improvements in valve gears, particularly adapted for use in locomotive engines, and one of the objects of the invention is to simplify the construction of valve gears, and at the same time dispense with the use of eccentrics, cams, et cetera.

15 A further object is to provide an improved device of this character wherein the valve may be adjusted or set to work within predetermined limits to control the lap and lead of the valve, and which may be readily and quickly adjusted to increase the 20 lap and lead of the valve, beyond such limits, or decrease the same at the will of the operator, and without necessitating the removing or detaching of any part of the 25 mechanism, or the substitution of other parts therefor.

30 A further object is to provide an improved valve gear of this character having means whereby the engine may be quickly reversed by the operation of a controlling lever, to shift the valve mechanism, and means whereby the valve may be readily adjusted to start the engine.

To the attainment of these ends and the 35 accomplishment of other new and useful objects, as will appear, the invention consists in the features of novelty in substantially the construction, combination and arrangement of the several parts, hereinafter 40 more fully described and claimed and shown in the accompanying drawing illustrating the invention, and in which—

45 Figure 1 is a diagrammatic view in elevation and partly in section of an improved valve gear of this character constructed in accordance with the principles of this invention. Fig. 2 is a view similar to Fig. 1, showing the parts in a different position. Fig. 3 is an enlarged detail sectional view 50 taken on line 3—3, Fig. 1.

55 Referring more particularly to the drawing and in the present exemplification of this invention, the numeral 10 designates the engine cylinder, 11 the piston, 12 the piston rod, 13 the reciprocating cross head to

which the piston 12 is connected, 14 the guide for the cross head and 15 the driving rod which is pivotally connected to the cross head, and all of which parts are of the ordinary and well known construction. 60

The valve 16 is of the reciprocating type and reciprocates across the ports or passages 19, 20, and also across the exhaust port 21, as is well known in engines of this character. A slide 22 is mounted to reciprocate upon a guide 23 and the valve stem 24 is adjustably connected with the slide 22 in any suitable manner, but preferably by passing through a suitable aperture in the slide and is secured to the slide by means 70 of nuts 25, engaging threaded portions of the rod 24 on opposite sides of the slide, thereby enabling the proper positioning of the valve with respect to the slide.

Pivots connected to the cross head 13 75 is a bell crank lever 26, one arm 27 of which is pivotally connected with one end of a member 28 as at 29, and the other end of the member is pivotally connected as at 30 with the rod 15. A jointed member comprising 80 the elements 31, 32 is provided between the slide 22 and the cross head 13, and the free end of the element 31 is pivotally connected as at 33 to the slide 22, while the free end of the element 32 of the jointed member is 85 pivotally connected as at 34 with the arm 35 of the bell crank lever 26. A member 36 is pivotally connected as at 29 with the arm 27 of the bell crank lever and the member 37 is connected as at 38 with the member 36 90 and is also detachably connected to a lug 39 carried by the member 31, and which lug 39 is preferably threaded to receive a nut for detachably securing the member 37 thereto. A second bell crank 40 is pivotally 95 mounted as at 41 to a fixed support and the arm 42 thereof is pivotally connected with the member 36, while the other arm of the bell crank is connected by means of a rod 43 with an operating lever 44 which co-operates 100 with a segment 45. The bell crank 40 constitutes a fixed fulcrum for the member 36, so that when the cross head 13 is reciprocated, the member 36 will rock about the pivot 46 and this rocking movement of the 105 member 36 will through the medium of the member 37 rock the element 31 of the jointed member about the fulcrum 33 and at the same time the slide 22 will be reciprocated on the guide 23 to actuate the valve 16. 110

The member 28 is provided as a means for holding the member 36 and the arm 27 of the bell crank 26 in the proper position.

When it is desired to cause the engine to advance, the lever 44 is moved to the position shown in Fig. 1 which will cause the parts to assume the positions shown in such figure, but when it is desired to reverse the engine, the lever 44 is moved to the position shown in Fig. 2 which will shift the parts accordingly, and the shifting of this lever 44 will position the valve 16 with respect to the ports 17, 18, 19 and 20 at the will of the operator. When the engine is shut down and it is desired to prevent steam from entering the cylinder, the lever 44 is shifted to a neutral position or to the position shown in dotted lines in Fig. 1 and in which position, the valve 16 will be moved to the dotted line position to close the ports 19, 20.

With this improved construction it will be manifest that the lever 44 may be shifted to position the valve 16 so that it will move or reciprocate within predetermined limits, that is to say, to cause the valve 16 to have a certain lap and lead with respect to the ports, but should it be desired to vary the lap or lead, this can be accomplished by first removing the stop pin 45^a and then adjusting the lever 44 still farther forwardly or backwardly with respect to the quadrant 45, without arresting the motion of the engine or any part thereof, and this variation in the lap or lead may be accomplished without removing any of the parts of the mechanism and without substituting or adding any parts thereto. If desired wear plates 47, 48 may be provided between the slide 22 and the guide 23.

In order to hold the member 31 in proper position, the upper extremities thereof may be bifurcated, as shown in detail in Fig. 3, one arm of the bifurcation being bent around the slide 22 and the extremities of the bifurcations being connected with the slide by means of the pivot pin 33.

With this improved construction it will also be manifest that all cams, eccentrics and eccentric straps are dispensed with and the parts are so arranged that ready access may be had thereto from the outside of the engine.

By the provision of the member 37, which is detachably connected as at 39 with the member 31, the parts may be readily assembled and during such assembling the parts may be properly adjusted and then the member 37 properly measured, after which the aperture for the lug 39 may be formed in the member, thereby insuring a proper aligning and adjustment of the parts during the initial assembling thereof. The parts are maintained in their adjusted positions by means of ordinary fastening provisions 49 of the quadrant 45 which coöperate with

the ordinary locking pawl, (the latter not being shown here).

While the preferred form, construction and arrangement of the several parts are herein shown and described, it is to be understood that numerous changes may be made in the details of construction and in the combination and arrangement of the several parts without departing from the spirit of this invention.

What is claimed as new is:—

1. A valve gear of the character described, embodying a reciprocating valve, a reciprocating cross head, a slide connected with the valve, a bell crank lever pivotally mounted directly upon the cross head, movable therewith and with respect thereto, a jointed member, one end of said member pivotally connected directly to the said slide, the other end of the member pivotally connected directly with one arm of the bell crank lever, the intermediate joint of said member being free, a second member pivotally connected by one end to the other arm of the bell crank lever, an operating lever connected with the said second member for actuating the latter to rock the bell crank, and a connection between the said second member, and that portion of the said jointed member which is connected with the said slide.

2. A valve gear of the character described, embodying a reciprocating valve, a reciprocating cross head, a slide connected with the valve, a bell crank lever pivotally mounted directly upon the cross head, movable therewith and with respect thereto, a jointed member, one end of said member pivotally connected directly to the said slide, the other end of the member pivotally connected directly with one arm of the bell crank lever, the intermediate joint of said member being free, a second member pivotally connected by one end to the other arm of the bell crank lever, an operating lever connected with the said second member for actuating the latter to rock the bell crank, and a connecting member pivotally and detachably secured to the said second member and that portion of the said jointed member which is connected with the said slide.

3. A valve gear of the character described, embodying a reciprocating valve, a reciprocating cross head, a slide connected with the valve, a bell crank lever pivotally mounted directly upon the cross head, movable therewith and with respect thereto, a jointed member, one end of the member pivotally connected directly with the said slide, the other end of the member pivotally connected directly with one arm of the bell crank lever, the intermediate joint of said member being free, a second member pivotally connected by one end to the other arm of the bell crank lever, an operating lever connected with the said second member for actuating the

latter to rock the bell crank, a connection between the said second member, and that portion of the said jointed member which is connected with the said slide, a driving rod connected with the cross head, and a connection between the said other end of the bell crank and the said driving rod, and pivotally secured to both.

4. A valve gear of the character described, embodying a reciprocating valve, a reciprocating cross head, a slide, an adjustable connection between the valve and slide, a bell crank lever pivotally mounted directly upon the cross head, and movable therewith, a jointed member pivotally connected at one end directly with the said slide and at its other end directly with one arm of the bell crank, the intermediate joint of said member being free, a second member pivotally connected by one end to the other arm of the bell crank, a connection between the said second member and that portion of the said jointed member which is connected with the said slide, and means for actuating the said second member to position the valve for a predetermined reciprocating movement, the said means also adapted to vary the extent of the reciprocating movement of the valve while the degree of movement of the valve gear remains constant.

5. A valve gear of the character described, embodying a reciprocating valve, a reciprocating cross head, a slide, an adjustable connection between the valve and slide, a bell crank lever pivotally connected directly with the cross head and movable therewith, a jointed member pivotally connected at one end directly with the said slide and at its other end directly with one arm of the bell crank, the intermediate joint of said member being free, a second member pivotally connected by one end to the other arm of the bell crank, a connection between the said sec-

ond member and that portion of the said jointed member which is connected with the said slide, means for actuating the said second member to position the valve for a predetermined reciprocating movement, the said means also adapted to vary the extent of the reciprocating movement of the valve while the degree of movement of the valve gear remains constant, and means for maintaining the parts in adjusted positions.

6. A valve gear of the character described, embodying a reciprocating valve, a reciprocating cross head, a slide, an adjustable connection between the valve and slide, a bell crank lever pivotally connected directly with the cross head and movable therewith, a jointed member pivotally connected at one end directly with the said slide and at its other end directly with one arm of the bell crank, the intermediate joint of said member being free, a second member pivotally connected by one end to the other arm of the bell crank, a connection between the said second member and that portion of the said jointed member which is connected with the said slide, and means for actuating the said second member to position the valve for a predetermined reciprocating movement, the said means also adapted to vary the extent of the reciprocating movement of the valve while the degree of movement of the valve gear remains constant, the said means embodying a shiftable element constituting a fixed fulcrum for the said second member.

In testimony whereof I have signed my name to this specification, in the presence of the subscribing witnesses, on this 8th day of September A. D. 1914.
